(57) **CLAIM**

The ornamental design for a wheeled support frame for an endless track, as shown and described.

DESCRIPTION

FIG. 1 is a front perspective view of a wheeled support frame for an endless track showing my new design;

FIG. 2 is a front view thereof;

FIG. 3 is a right end view thereof;

FIG. 4 is a left end view thereof;

FIG. 5 is a top plan view thereof;

FIG. 6 is a bottom plan view thereof; and,

FIG. 7 is a rear view thereof.

Portions of the wheeled support frame for an endless track shown in broken lines are for illustrative purposes only, and form no part of the claimed design.
